(57) **CLAIM**

The ornamental design for a control box for image display device, as shown and described.

DESCRIPTION

FIG. 1 is a perspective view of a control box for image display device;

FIG. 2 is a front view thereof;

FIG. 3 is a top view thereof;

FIG. 4 is a left-side view thereof;

FIG. 5 is a right-side view thereof;

FIG. 6 is a rear view thereof;

FIG. 7 is a bottom view thereof;

FIG. 8 is an enlarged view of an area shown in a box labeled “8” in FIG. 1;

FIG. 9 is an enlarged view of an area shown in a box labeled “9” in FIG. 2;

FIG. 10 is an enlarged view of an area shown in a box labeled “10” in FIG. 3;

FIG. 11 is a cross-sectional view taken along a line 11-11 in FIG. 9;

FIG. 12 is a cross-sectional view taken along a line 12-12 in FIG. 10; and,

FIG. 13 is another perspective view showing the control box for image display device in use with a head mounted image display device.

The broken lines depict environmental subject matter only and form no part of the claimed design. The dot-dash lines depict a boundary between claimed and unclaimed subject matter, and form no part of the claimed design.
